CLAIM

The ornamental design for a storage box, as shown and described.

DESCRIPTION

FIG. 1 is a front view of a storage box showing our new design;

FIG. 2 is a rear view thereof;

FIG. 3 is a right side view thereof, the left side view being a mirror image;

FIG. 4 is a top view thereof;

FIG. 5 is a bottom view thereof;

FIG. 6 is a perspective view thereof;

FIG. 7 is a front view of the storage box in an open state;

FIG. 8 is a rear view thereof;

FIG. 9 is a right side view thereof, the left side view being a mirror image;

FIG. 10 is a top view thereof;

FIG. 11 is a bottom view thereof; and,

FIG. 12 is a perspective view thereof.

(Continued)

The broken lines illustrate portions of the storage box. The dash-dot-dash line broken lines illustrate the bounds of the claim. None of the broken lines or area within form part of the claimed design.

1 Claim, 12 Drawing Sheets
